US0D1063223S

(12) **United States Design Patent** (10) Patent No.: **US D1,063,223 S**
(45) Date of Patent: **** Feb. 18, 2025**

(54) **PROTECTIVE HELMET**

(71) Applicant: **SCP GEORGE TFE**, Monaco (MC)

(72) Inventor: **James Rogers**, Cumbria (GB)

(**) Term: **15 Years**

(21) Appl. No.: **35/516,059**

(22) Filed: **Dec. 20, 2022**

(80) **Hague Agreement Data**

Int. Filing Date: **Dec. 20, 2022**

Int. Reg. No.: **DM/226035**

Int. Reg. Date: **Dec. 20, 2022**

Int. Reg. Pub. Date: **Jan. 20, 2023**

(51) **LOC (15) Cl.** **02-03**

(52) **U.S. Cl.**

USPC **D29/102**

Primary Examiner — Leanne Was-Englehart

Assistant Examiner — Justin A Johnson

(57) **CLAIM**

The ornamental design for a protective helmet as shown and described.

DESCRIPTION

1. Protective helmet

1.1 : Perspective

1.2 : Front

1.3 : Right

1.4 : Back

1.5 : Left

1.6 : Top

1.7 : Bottom

1.8 : perspective view rear

1 Claim, 8 Drawing Sheets
